(57) **CLAIM**

The ornamental design for a boat cleat, as shown and described.

DESCRIPTION

FIG. 1 is a bottom perspective view of the boat cleat of the present invention, wherein the cleat head is pulled upwardly from the cleat base so as to be in a use position.

FIG. 2 is a top perspective view of the boat cleat of the present invention in the use position.

FIG. 3 is an end elevation view of the cleat in the used position, with the opposite end being identical.

FIG. 4 is a side elevation view of the cleat in the used position, with the opposite side being identical; and,

FIG. 5 is a top plan view of the cleat.

The structure shown by broken lines does not constitute part of the present invention.
